(57) **CLAIM**

The ornamental design for a hose-to-mattress connection assembly, as shown and described.

DESCRIPTION

FIG. 1 is a front elevational view of the male portion of the hose-to-mattress connection assembly of the present invention;

FIG. 2 is a rear elevational view of the male portion of the hose-to-mattress connection assembly of FIG. 1;

FIG. 3 is a left side elevational view of the male portion of the hose-to-mattress connection assembly of FIG. 1;

FIG. 4 is a right side elevational view of the male portion of the hose-to-mattress connection assembly of FIG. 1;

FIG. 5 is a top view of the male portion of the hose-to-mattress connection assembly of FIG. 1;

FIG. 6 is a bottom view of the male portion of the hose-to-mattress connection assembly of FIG. 1;

FIG. 7 is a perspective view of the male portion of the hose-to-mattress connection assembly of FIG. 1;

FIG. 8 is a front elevational view of the female portion of the hose-to-mattress connection assembly of the present invention;

FIG. 9 is a rear elevational view of the female portion of the hose-to-mattress connection assembly of FIG. 8;

FIG. 10 is a left side elevational view of the female portion of the hose-to-mattress connection assembly of FIG. 8;

FIG. 11 is a right side elevational view of the female portion of the hose-to-mattress connection assembly of FIG. 8;

FIG. 12 is a top view of the female portion of the hose-to-mattress connection assembly of FIG. 8;

FIG. 13 is a bottom view of the female portion of the hose-to-mattress connection assembly of FIG. 8;

FIG. 14 is a perspective view of the female portion of the hose-to-mattress connection assembly of FIG. 8;

FIG. 15 is perspective view showing the male portion of the hose-to-mattress connection assembly of FIG. 1 aligned with the female portion of the hose-to-mattress connection assembly of FIG. 8; and,

FIG. 16 is another perspective view showing the male portion of the hose-to-mattress connection assembly of FIG. 1 aligned with the female portion of the hose-to-mattress connection assembly of FIG. 8, but further showing the female portion positioned on a mattress and the male portion connected to a hose.

The broken lines shown in FIG. 16 represents the environment of the claimed design and forms no part thereof.

1 Claim, 10 Drawing Sheets
